UNITED STATES PATENT OFFICE.

HARVEY DIKEMAN, OF DANBURY, CONNECTICUT.

GRATE-OPERATING APPARATUS.

1,112,527.

Specification of Letters Patent.

Patented Oct. 6, 1914.

Application filed April 13, 1914. Serial No. 831,661.

To all whom it may concern:

Be it known that I, HARVEY DIKEMAN, citizen of the United States, residing at Danbury, in the county of Fairfield and State 5 of Connecticut, have invented certain new and useful Improvements in Grate-Operating Apparatus, of which the following is a specification.

This invention relates to improvement in 10 the apparatus for actuating fire grates, and may be applied without material structural change to the grates of cooking stoves, ranges, furnaces, steam and other generators, and the like, and has for one of its 15 objects to improve the construction and to render the operation more certain and increase the efficiency and utility of devices of this character.

With these and other objects in view the 20 invention consists in certain novel features of construction as hereinafter shown and described and then specifically pointed out in the claims.

The improved device is designed more 25 particularly for use in connection with cooking stoves and ranges, and for the purpose of illustration is shown applied to the fire-box and grate portion of a conventional cooking range, and in the drawings thus 30 employed—Figure 1 is an end elevation of the fire-box portion of a cooking range with the improved grate actuating mechanism applied. Fig. 2 is a plan view with the fire-box portion in section on the line 2—2 35 of Fig. 1. Fig. 3 is a section on the line 3—3 of Fig. 2. Fig. 4 is a detached perspective view of the coupling bar.

Corresponding and like parts are referred to in the following description and indicated 40 in all the views of the drawings by the same reference characters.

The fire-box portion of the range is indicated as a whole at 10 and includes bearings 11 for the trunnions 13—14 of the grate 45 members, the latter being designated conventionally at 15—16. Any required number of the grate sections may be employed and it is not desired therefore to limit the invention in this respect, but for the purpose 50 of illustration two of the sections arranged to be rocked upon their trunnions are shown. The grate bars are shown in the usual form, but any required arrangement of the bars may be employed. The trunnions 13—14 at 55 one end are extended and formed with

squared terminals 17—18 externally of the side wall of the range. Mounted upon the terminal 17 of the trunnion 13 is an arm 19, while a similar arm 20 is mounted upon the terminal 18 of the trunnion 14. The arms 19—20 extend above and below the terminals 17—18 and are connected respectively at their upper and lower ends by links 21—22, the links being pivoted to the arms as shown. The links 21—22 are coupled intermediate 60 their ends by a bar 23 which is pivoted to the links at 24—25. The bar 23 is provided with a socket 26 to receive one end 27 of an operating handle 28, the portions 27—28 being preferably formed at right angles to 70 each other as represented in Fig. 2. By this simple arrangement it will be obvious that by coupling the handle member to the socket and moving the handle back and forth simultaneous oscillating motion will be imparted to the coupled grates, and with equal force above and below the trunnions, so that 75 no danger exists of unequal strains being applied to the grates. By this arrangement also it will be obvious, that no danger exists 80 of one grate section being moved faster or to a greater extent than the other, but all the grate sections will be simultaneously actuated and in perfect harmony and at uniform speed and each section likewise moved to 85 exactly the same extent. Thus, no danger exists of one or more of the grate sections being overturned or becoming otherwise displaced.

By arranging the terminals 17—18 of the 90 trunnions intermediate the arms 19—20 and applying the locking force to the arms at equal distances from their pivotal points, the leverage or the force will be correspondingly uniformly applied to the grate bars 95 and all tendency to unequal strains obviated.

The improved device is simple in construction, can be inexpensively manufactured and applied without material structural change to the various forms of rolling grate sections in common use.

Having thus described the invention, what is claimed as new is:

1. The combination with a grate device 105 including a plurality of rocking units, of arms connected intermediate their ends respectively to said units, links pivotally connected to said arms at equal distances from the grate unit connections thereof, a member 110

pivottally connected to said links, and means for imparting movement to said link connecting member.

2. The combination with a grate device including a plurality of rocking units, of arms connected intermediate their ends respectively to said units, links pivotally connected to said arms at equal distances from the grate unit connections thereof, and means for imparting reciprocating movement to said links.

3. The combination with a grate device including a plurality of rocking units, of arms connected intermediate their ends respectively to said units, links pivotally connected to said arms at equal distances from the grate unit connections, a member pivot-

ally connected to said links and having a socket, and an operating member engaging said socket.

20

4. The combination with a grate device including a plurality of rocking units, of arms connected intermediate their ends respectively to said units, links pivotally connected to said arms above and below said grate connections, and means for imparting reciprocating movement to said arms and their link connections.

25

In testimony whereof I affix my signature in presence of two witnesses.

HARVEY DIKEMAN. [L.S.]
